ROOFING

Hadi King, Redondo Beach, Calif.

Application June 3, 1946, Serial No. 674,096

9 Claims. (Cl. 108—7)

1

This invention relates to roofing and, particularly, to that type of roofing composed of flexible sheet material so cut as to simulate, when laid, the appearance of individual shingles.

One difficulty encountered in many types of sheet roofing of this character is that the edges of the shingle tabs tend to warp due to the heat of the sun, or are often turned up by the wind.

It is therefore an object of the present invention to provide sheets of roofing elements of this character which include means for locking the exposed portions of the shingle tabs so as to prevent their becoming loosened by the wind, or warped by moisture and heat.

Another object of the invention is to provide an improved locking means for shingles of this character.

Still another object of the invention is to provide a roofing of this character which will not leak when laid.

A further object of the invention is to provide roofing of this character which will present an improved and attractive appearance.

A still further object of the invention is to provide roofing of this character which readily lends itself to a variety of attractive designs.

Another object of the invention is to provide roofing of this character which may be medially cut by a cutting machine and rolled without separation along the cut so that each part of the original strip may be used and the shingle tabs will be protected in the package.

Still another object of the invention is to provide roofing of this character which is relatively easy to apply.

Another object of the invention is to provide roofing of this character which may be made of plastic material.

Further objects and advantages of the invention will be brought out in the following part of the specification.

Referring to the drawings, which are for illustrative purposes only,

Fig. 1 is a plan view showing a portion of a sheet of roofing embodying the present invention;

Fig. 2 is a plan view showing a portion of a laid roof embodying the present invention;

Fig. 3 is a section taken on the line 3—3 of Fig. 1;

Fig. 4 shows an alternative arrangement of the invention; and

Fig. 5 shows still another alternative arrangement thereof.

Referring to Figs. 1, 2 and 3, there is shown

roofing of the strip type, comprising a body portion 10 having a straight marginal side edge 11. The other marginal side portion is cut to provide alternate recesses, indicated generally at 12, and 5 shingle tabs, indicated generally at 13. Each recess is bounded by a straight side 14 extending transversely of the body 10 and a short straight edge 15 extending parallel to the edge 11. Oppositely the side 14 there is an outwardly extending side portion 16 which is parallel to the side 14, and an inclined side portion 17 which diverges from said side 14. From the outer end of the diverging side portion 17 there is a laterally extending side portion 18 which is also parallel to 15 the side 14.

The tab thus formed by cutting out the recesses has an outwardly extending portion 19 with parallel sides which are bounded by the edge 16 and a portion of the edge 14, a portion 20 23 which is bounded by the edge 17 which converges with respect to the adjacent edge 14 of the shingle and another portion of the edge 14, and terminates at its outer end in a tongue 21 which is bounded by the edge 18 and the remaining 25 portion of the edge 14. The free end 22 of the shingle tab is substantially parallel with the edge 11.

Adjacent the deepest part of each recess is a slot 23 in the body portion 10 which extends 30 diagonally relative to the edge 11. The slots 23 are of sufficient length to receive the tongues 21 of the shingles, and when the strips of roofing are laid with the shingle tabs staggered, as shown in Fig. 2, the tongues 21 and a corner portion of the 35 part 23 of the shingle tabs are received in the slots so that the exposed shingle presents a pointed appearance at its lower extremity.

In laying the roofing a starting strip 24, having 40 diagonal slots 23, is put down first at the lower edge of the roof and secured by nails 25 of suitable character, which are well known in the roofing art. The nails may be spaced approximately 12 inches apart at the top, or any other suitable distance, said nails being disposed adjacent the straight marginal edge 11 of the strip. 45 If desired, nail holes 26 may be formed in the roofing strip when it is cut.

After the starting strip is laid, the next adjacent strip is laid and nailed, said strip also having 50 the prepunched nail holes 26, and the tongues 21 then inserted in the slots 23 of the starting strip. This procedure is then followed for succeeding strips, the tongues 21 of each added strip being inserted in the slots 23 of the previously laid strip. 55 It is to be understood that the strips are laid so

as to stagger the shingle tabs for alignment with the notches of the preceding strip.

When the roofing is laid, the nails of a lower strip are covered by the body portion 10 of the strip immediately above it, and the slots of the strips are underlaid by the body portion 10 of the strip immediately below it. Thus, water is prevented from penetrating through the laid strips and an attractive design is presented.

Due to the length of the tabs 22, and the additional amount of the portion 20 of the shingles which extend through the respective slots because of the diagonal slot, a secure locking of the shingles is provided which will prevent said shingles from being upturned or twisted by the wind, and will also prevent warping of the shingles under the influence of heat and moisture.

Referring to the arrangement shown in Fig. 4, the shingle tabs 28 of the shingle strip have an irregular outline and are separated by recesses 29 which also have an irregular outline, being defined by the adjacent edges of the shingle tabs. Each shingle tab terminates in a pointed portion 30 which, when the roofing is laid, is adapted to be received in a diagonal slot 23. The pattern of the laid shingles of this configuration presents a futuristic appearance, as brought out in said Fig. 4.

Referring to Fig. 5, there is shown another alternative arrangement wherein the serrated marginal portion includes recesses 35 between longitudinally spaced shingle tabs 36, said tabs having pointed ends 37 which are received in V-shaped slots 38 in the body portion 10. The slots 38 are cut in the body portion adjacent the recesses 35. This arrangement of the shingles, together with their particular shape, provides still another pattern when installed on a roof.

The roofing may be made of any suitable material that is flexible, tough and waterproof. If desired, the shingle strips may be made of a plastic material which is also fire retarding and which may be provided in various colors. An example of such material is "Vinylite," although other types of plastic or other suitable roofing material may be used. The roofing strips may be all of one color for a roof, or they may be of various colors so as to provide a vari-colored roof pattern.

The roofing may be easily applied and no cement is needed for securing the shingle tabs or other parts. In fact, the application is relatively simple and may be rapidly made.

It is to be understood that the slot 23 shown in Figs. 1 to 4 may be inclined in the opposite direction in the case of some designs.

I claim:

1. In a shingle strip formed of flexible material, comprising: a body portion having one substantially straight marginal edge, the other marginal side being so shaped as to provide alternating recesses and shingle tabs of reduced size adjacent their free ends, said body portion having slots adjacent the respective recesses, extending diagonally with respect to said straight edge, the free end portions of the shingle tabs being received in respective slots of an underlying strip.

2. In a shingle strip formed of flexible material, comprising: a body portion having one substantially straight marginal edge, the other marginal side of the strip being provided with alternating recesses and shingle tabs, said body portion having slots adjacent the respective recesses, extending diagonally with respect to said straight edge, and a tongue extending from the free end of each

shingle tab adapted to be received a substantial distance in respective slots in an underlying strip, there also being a portion of the shingle tab, adjacent the tongue, received in the respective slots.

5. In a shingle strip formed of flexible material, comprising: a body portion having one substantially straight marginal edge, the other edge being irregular in shape to provide alternating recesses and shingle tabs having an offset end portion, said shingle tabs being of irregular shape and having substantially pointed free end portions, and said body portion having slots adjacent the respective recesses, extending diagonally with respect to said straight edge and adapted to receive therein the said end portions of an overlying strip so that when the sheets are laid on a roof there is provided a pattern of irregularly shaped shingles.

20 4. In a roofing sheet formed of flexible material, comprising: a body portion having a substantially straight marginal side edge and having a marginal side portion, opposite the first mentioned side, provided with alternate recesses and shingle tabs, each of said shingle tabs having one side defined by a substantially straight edge extending transversely of the body portion and having the other side bounded by a short edge portion substantially parallel with the other edge portion, a tapering edge portion and a second edge portion parallel to the first mentioned edge portion and terminating in an edge portion substantially parallel with the straight edge portion of the body to thereby provide an offset tongue extending from the shingle tabs; said body portion having slots, adjacent respective recesses extending diagonally with respect to said straight edge and adapted to receive respective tongues of the shingles of an overlying strip.

25 5. The invention defined by claim 4, wherein the slots are disposed over the body portion of an underlying strip when the roofing is laid.

6. As a new article of manufacture: a flexible roofing strip having a body portion with a substantially straight edge along one side and an irregular edge along the other side, forming alternating recesses and shingle tabs of angularly shaped sides, a tongue extending from each shingle tab and offset from the longitudinal center of said tab, said body portion having slots adjacent the respective recesses extending diagonally with respect to the straight edge thereof and adapted to receive said tongue and a free edge portion of respective shingle tabs of an adjacent strip when laid on a roof.

7. The invention defined by claim 6, wherein said roofing strip is composed of a plastic material.

60 8. In a shingle strip formed of flexible material, comprising: a body portion having one side edge substantially straight, the marginal portion of the other side being so shaped as to provide alternating recesses and shingle tabs having tapered end portions, said body portion having V-shaped slots adjacent the respective recesses for reception of the free end portions of shingle tabs of an adjacent strip, said slots being substantially parallel with the edges of the tapered end portions when inserted therein.

65 9. In a roofing sheet formed of flexible material, comprising: a body portion having a substantially straight marginal side edge and having a marginal side portion, opposite the first mentioned side, provided with alternate recesses and shingle tabs, each of said shingle tabs hav-

ing one side defined by a substantially straight edge extending transversely of the body portion and having the other side bounded by a short edge portion substantially parallel with the other edge portion, a tapering edge portion and a second edge portion parallel to the first mentioned edge portion and terminating in an edge portion substantially parallel with the straight edge portion of the body; said body portion having slots, adjacent respective recesses and 10 adapted to receive respective tongues of the shingles of an overlying strip.
